UNITED STATES PATENT OFFICE.

CLAUD L. LONG, OF DAYTON, OHIO, ASSIGNOR TO THE CRAWFORD, McGREGOR AND CANBY COMPANY, A CORPORATION OF OHIO.

TURNING-HEAD FOR WOODWORKING-MACHINES.

1,370,825.

Specification of Letters Patent.

Patented Mar. 8, 1921.

Application filed January 3, 1919. Serial No. 269,542.

To all whom it may concern:

Be it known that I, CLAUD L. LONG, a citizen of the United States, residing at Dayton, in the county of Montgomery and 5 State of Ohio, have invented certain new and useful Improvements in Turning-Heads for Woodworking-Machines, of which the following is a specification.

My invention relates to cutter heads for 10 wood working machines and particularly to a rotary cutter head for pattern or variable shape lathes.

The object of the invention is to modify 15 the structure as well as the means and mode of operation of such devices, whereby they will not only be cheapened in construction, but will be more efficient in use, and unlikely to get out of repair.

While cutter heads employing hollow or 20 cup shaped cutters, and cutters revolvably mounted to present unused cutting edges to the work by the rotation of the cutters, are already well known in the art, such cutters have usually been mounted in positions sub- 25 stantially perpendicular to the plane of rotation of the head which it is found in practice does not result in highest efficiency. To increase the efficiency of this type of cutter heads by mounting the cutter blades in positions inclined to the plane of rotation and 30 inclined one to the other, is one of the primary objects of the invention.

The modified form of cutter head herein disclosed is designed to afford a more or less 35 drawing cut due to the inclination of the blades, to afford an increased degree of clearance, and to facilitate the "lead" of the cutter head into the work.

With the above primary and other incidental objects in view, as will more fully 40 appear in the specification, the invention consists of the features of construction, the parts and combinations thereof, and the mode of operation, or their equivalents, as 45 hereinafter described and set forth in the claims.

Referring to the drawings, Figure 1 is a 50 side elevation of a cutter head as applied to turning shoe lasts. Fig. 2 is an end view of the cutter head. Fig. 3 is a side elevation thereof. Figs. 4 and 5 are views of the head with the cutters removed, from different right angle positions, showing the relation of the cutter supporting lugs. Fig. 6 is 55 a view of the head having the cutters set

at an inclination or angle in two directions. Figs. 7 to 11 illustrate modifications. Fig. 12 is a detail sectional view of one of the cutter members.

Like parts are indicated by similar characters of reference throughout the several views.

The cutter head forming the subject matter hereof comprises a main body portion or supporting head 1 adapted to be carried 60 upon a rotary spindle or other driving element 2. Projecting from the terminal face of the body portion 1 are two cutter supporting lugs 3—3 located upon diagonal quadrants of the said body portion. The 65 oppositely disposed cutter supporting faces 4 of these lugs are inclined or divergent in relation one to the other and to the axis and plane of rotation. The degree of divergence 70 shown in the drawing is such that said lugs 75 approach quite closely to the center line of the head at their bases, being separated at their bases a distance very much less than the thickness of the cutters to be carried, while at their extremities the lugs are separated 80 a distance much greater than the thickness of the cutters. The degree of divergence may be varied in accordance with the work to be performed and the character 85 of the material operated upon. However 85 approximately the angle shown will be found quite suitable for general use.

Mounted upon the inclined faces of the lugs in overlapping relation, but inclined in relation one to the other are two cup shaped 90 cutters 5. The exterior of the cutters has been shown somewhat tapered or of frustoconical form, although in view of their inclined positions straight or cylindrical forms of cutters will be afforded sufficient 95 clearance. The cutters 5 are revolvably mounted upon central studs 6 screw threaded into the lugs 3. As a convenient means of retaining the revolvable cutters in their adjusted positions studs 7 are provided in 100 the faces 4 of the lugs, which studs engage any one of a series of holes 8 in the web or base of the corresponding cutter. By loosening the cutter stud 6 and disengaging the cutter from the positioning stud or pin 105 7 the cutter may be rotated and the pin or stud 7 reengaged with a different hole 8, thereby presenting an unused portion of the cutting edge in operative position.

This rotation of the cutters is merely a 110

matter of convenience and it is to be understood that sector shaped cutters having fixed relation with the lugs may be employed.

- 5 The cutters being mounted side by side but in transverse planes approach quite closely at their inner sides, but preferably do not touch one upon the other. The diameter of the cutters shown in Figs. 2, 3
10 and 6 is thus substantially equal to the maximum radius of the head. The whole comprises a comparatively small compact arrangement of the cutters and their support whereby they are enabled to operate 15 within arcuate recesses of comparatively small radius.

While the construction shown in Figs. 2 to 5 affords a diagonal or draw cut so long as the work is engaged at the side of the head as shown by the dotted lines of Fig. 1, this diagonal relation of the cutting edge to the plane of rotation of the work at the point of operation decreases as the point of operation of the cutting edge approaches 25 the point shown by solid lines of Fig. 1 unless the cutters are set at an inclination or angle in two directions as shown in Fig. 6. This is a desirable arrangement though not essential for all shapes to be turned.
30 As shown in Fig. 6 the cutters are not only inclined to the plane of rotation as in the preceding figures, but are also inclined in the plane of rotation of the head, so that one side preferably the inner side, radially
35 considered, is slightly in advance of the outer side of the cutter in relation with the direction of rotation. Thus instead of the cutters being radially disposed in relation with the supporting head they are somewhat tangentially arranged. This affords a diagonal or shearing cut at any point of the cutting edge.

While cutters of small diameter are essential for turning extreme shapes, for ordinary conditions of use a larger cutter is to be preferred as it affords a cut of greater length as compared with its depth, that is to say the cut is more flat and will necessitate less finishing to remove the cutter marks from the work.

In Figs. 7 and 8 there are shown a perspective view and side elevation respectively of a modification in which may be employed circular cutters of either greater or less diameter than the radius of the assembled head. Instead of two spaced lugs diagonally positioned and having oppositely inclined adjacent faces as described, the form shown in Figs. 7 and 8 embodies a main body 9 having a single wedge shaped or tapered terminal lug 10 the opposite faces of which being inclined one to the other receive the circular cutters 5. If so desired the cutters may be of a size to overlap in

relation with each other. Or they may be 65 substantially equal in diameter to the radius of the assembled head or less than such radius. The cutters being mounted upon the oppositely disposed inclined faces will be inclined to the plane of rotation and to 70 each other.

Double blade cutter heads such as shown in Figs. 1 to 8 inclusive necessitate great accuracy in manufacture and adjustment of the parts to insure equal cutting action by 75 both cutters. Unless accurately constructed one cutter will perform all the work and the other operating idly will merely serve as a balance weight for the rotating head. In Figs. 9 to 11 there is disclosed a form of 80 cutter head having but one circular cutter, 11 the second cutter being replaced by a mass of metal 12 which serves as a counter balance and performs all the functions of 85 the second cutter of a double cutter head the cutters of which have been misplaced or unevenly worn. The construction shown permits the use of a larger circular cutter 11 which affords a broader chip while maintaining the balanced relationship of the 90 head as found in the double cutter construction. The cutter 11 is not only inclined to the plane of rotation, but is somewhat tangentially arranged in relation with the center of rotation. The mounting and adjustment of the cutter is the same as previously 95 described.

From the above description it will be apparent that there is thus produced a device of the character described, possessing the 100 particular features of advantage before enumerated as desirable but which obviously is susceptible of modification in its form, proportion, detail construction, and arrangement of parts without departing 105 from the principle involved or sacrificing any of its advantages.

Having thus described my invention I claim:

1. A rotary cutter comprising a body portion having lugs projecting from its end, said lugs having opposed inclined mounting faces spaced apart a distance less than the thickness of the cutters at their bases and greater than the thickness of the cutters at 110 their extremities, cup shaped cutters with annular cutting edges the diameter of which is substantially equal to the length of the radius of the cutter head, and means for mounting the cutters upon the mounting 115 faces in inclined relation with each other and with their inner sides in juxtaposition with each other.

2. A rotary cutter comprising a body portion, supporting lugs projecting from the 125 terminal face thereof having substantially radially disposed mounting faces inclined to the plane of rotation, and cutter members

- mounted upon said inclined faces engaging the work in directions substantially perpendicular to the planes of said faces, the cutting edges of said members being located in offset divergent planes, substantially as specified.
3. A rotary cutter of that type embodying a main body, supporting lugs carried thereby and circular cup shaped cutters carried by the lugs, characterized by having said cutters arranged in divergent planes substantially perpendicular to the plane of rotation but slightly inclined rearwardly in relation with the direction of rotation of the head.
- 10 4. A rotary cutter head comprising a body portion and a plurality of circular cup shaped cutters carried thereby, said cutters being arranged with their cutting edges in different planes substantially radially disposed in relation with the axis of rotation, but inclined rearwardly in relation with the direction of rotation of the cutter head.
- 20 5. A rotary cutter head comprising a supporting body having an inclined mounting face thereon, and an arcuate cutter mounted thereon, the plane of said cutter being substantially radial in relation with the axis of rotation of the head with its cutting edge inclined both to and in the plane of rotation.
- 25 6. A rotary cutter head comprising a supporting body having an inclined mounting face, and an arcuate cutter mounted upon the inclined face in a position offset in the plane of the cutter in relation with the axis of rotation, said cutter being substantially perpendicular to the plane of rotation, but
- 30
- 35
- 40
- 45
- 50
- 55
- 60
- 65
- slightly inclined rearwardly in relation with the direction of rotation.
7. A rotary cutter head comprising a supporting body having an inclined face, and an arcuate cutter mounted thereon in a position offset in the plane of the cutter in relation with the axis of rotation, the plane of the cutter being tangential in relation with the axis of rotation and inclined in relation to the plane of rotation.
8. In a cutter of the character described a supporting body and two cutter disks arranged side by side each in a plane substantially perpendicular to the plane of rotation but tilted slightly rearward in relation with the direction of rotation.
9. In a cutter of the character described, a rotary supporting head, a cutter carried thereby in a plane substantially perpendicular to the plane of rotation, but tilted slightly rearward in relation with the direction of rotation.
10. In a cutter a rotary supporting body, a cutter supporting lug projecting from the terminal face thereof, slightly inclined to the plane of rotation, and a cutter member mounted upon the inclined lug having its face turned in the direction of rotation, substantially as specified.

In testimony whereof, I have hereunto set my hand this 19th day of December, A. D. 1918.

CLAUD L. LONG.
